CLAIM

The ornamental design for a solar light, as shown and described.

DESCRIPTION

FIG. 1 is a top perspective view of a solar light showing Embodiment 1;
FIG. 2 is a bottom perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a top perspective view thereof in a use state;
FIG. 10 is bottom perspective view thereof in another use state;
FIG. 11 is a top perspective view of the solar light showing Embodiment 2;
FIG. 12 is a bottom perspective view thereof;
FIG. 13 is a front view thereof;
FIG. 14 is a rear view thereof;
FIG. 15 is a left side view thereof;
FIG. 16 is a right side view thereof;
FIG. 17 is a top view thereof;
FIG. 18 is a bottom view thereof;
FIG. 19 is a top perspective view thereof in a use state;
FIG. 20 is bottom perspective view thereof in another use state;
FIG. 21 is a top perspective view of the solar light showing Embodiment 3;
FIG. 22 is a bottom perspective view thereof;
FIG. 23 is a front view thereof;
FIG. 24 is a rear view thereof;
FIG. 25 is a left side view thereof;
FIG. 26 is a right side view thereof;
FIG. 27 is a top view thereof;
FIG. 28 is a bottom view thereof;
FIG. 29 is a top perspective view thereof in a use state; and,
FIG. 30 is bottom perspective view thereof in another use state.

The broken lines in the drawings illustrate the portions of the solar light, which form no part of the claimed design.
